UNITED STATES PATENT OFFICE.

ALVA D. JONES, OF PHILADELPHIA, PENNSYLVANIA.

SOUND-BOX FOR TALKING-MACHINES.

1,275,936.

Specification of Letters Patent. Patented Aug. 13, 1918.

Application filed November 23, 1914. Serial No. 873,500.

To all whom it may concern:

Be it known that I, ALVA D. JONES, a citizen of the United States, residing in the city and county of Philadelphia, State of Pennsylvania, have invented a new and useful Sound-Box for Talking-Machines, of which the following is a specification.

In sound boxes for talking machines as generally constructed, it is well known that 10 the same in use frequently emit a metallic or scratchy sound accompanying the reproduction of sound from the sound reproducing tablet.

I have discovered as the result of an extensive series of experiments, that rubber when properly cured to the requisite extent so as to attain a degree of hardness or resiliency simulating the condition of the human throat or palate, possesses many characteristics of the human throat when employed for a sound reproducing agent, and by constructing the operative portion of the sound box which coacts with the diaphragm, of a thickened, hardened wall of rubber or 25 similar material and assembling the diaphragm with respect thereto, in such a way that said diaphragm is capable of the requisite movement at its outer and central portions, I have produced a device whereby the 30 sound delivered from the diaphragm is greatly mellowed and improved, and a clear and distinct articulation is obtained.

To the above ends, my invention consists of a novel construction of sound box wherein 35 the principal portion thereof which coöperates with the diaphragm is constructed of a hardened and somewhat thickened wall of rubber or the like cured to a degree of hardness simulating the human throat or palate, 40 said wall having secured thereto a metallic ring, plate or casting having thereon arms provided with bearings for the stylus bar, whereby a device is cheaply produced having peculiar recording or reproducing qualities, and wherein any surface sounds or 45 metallic or scratchy noises are eliminated or absorbed in said hardened, thickened wall of the sound box, the resultant device having peculiar reproducing qualities which 50 closely resemble the action of the human throat or palate in reproducing sounds.

My novel sound box and its adjuncts are inexpensive to construct, extremely sensitive in action, easily and quickly repaired, and 55 readily accessible for the purposes of inspection or replacement of parts, means be-

ing thus provided for a general improvement of the vocal or instrumental tones, and amelioration of the surface noises, as well as of the scratchy metallic or grinding sounds common in instruments of this class, and provision is thus made for a faithful development and recording or reproduction of delicate sounds ordinarily difficult to reproduce, which are reproduced by my novel device with a maximum degree of fidelity and faithfulness to the original.

For the purpose of illustrating my invention, I have shown in the accompanying drawings, certain forms thereof which are at present preferred by me, since the same will be found in practice to give satisfactory and reliable results, although it is to be understood that the various instrumentalities of which my invention consists can be variously arranged and organized, and that my invention is not limited to the precise arrangement and organization of these instrumentalities as herein shown and described.

Figure 1 represents a front elevation of a sound box embodying my invention.

Fig. 2 represents a section on line $\alpha-\alpha$ Fig. 1.

Fig. 3 represents a sectional view of a modified form of construction embodying the principles seen in Fig. 1.

Fig. 4 represents a sectional view of another embodiment of my invention.

Fig. 5 represents a front elevation of Figs. 3 and 4, showing the preferred manner of mounting the stylus bar in its bearings.

Fig. 6 represents a sectional view of another embodiment of my invention.

Fig. 7 represents a sectional view of the gasket device seen in Fig. 6, before the same is bent into the position seen therein. Fig. 8 represents a front view of the disk of Fig. 6.

Similar numerals of reference indicate corresponding parts in the figures.

Referring to the drawings:

Referring first to Fig. 2, 1 designates my novel construction of sound box, the same comprising the hardened, thickened disk 105 wall or body portion 2, which is preferably constructed of rubber or similar material, which is cured to a condition closely simulating the human throat or palate, said body portion being provided with an extension 3, which is somewhat softer than the body 2, and which is adapted to frictionally engage

the contiguous portion of the tube or tone arm 4.

5 designates a metallic ring which is provided with screw threads adapted to engage the exterior screw-threaded portion of the wall or body 2, said ring being provided with an annular, recessed portion 6, which provides room for the requisite play of the diaphragm 7, which is held between the rubber annuli 8, the inner one of said annuli being seated in a suitable groove in the body portion 2, while the outer annulus 8 is contained within a suitable recess 9 contained in the overhanging flange 10. The stylus bar 11 is secured to the diaphragm in any approved manner, and has at its lower portion a head 12, which is pivotally mounted between the pivot points 13 of the screws 14, there being two of the latter which are in threaded or other engagement with the bearings 15, which are carried on the arms 16 secured or cast upon the outer ring 5. If desired, a suitable cementing or adhesive material or composition may be interposed between the contiguous threaded portions of the ring 5 and the body portion 2, so that when these parts are assembled, they will be permanently and rigidly connected together, so that no chattering or vibration will be possible by reason of the union of the metal or other ring 5 with the thickened, hardened rear wall or disk 2 of rubber or other suitable material.

In the construction seen in Fig. 3, 16 designates the hardened wall or body portion of rubber or similar material, the same being inclosed by the outer ring 17, which may be of metal or similar material, there being a lining of cement 18 interposed between the ring 17 and the outer periphery of the rubber wall or disk 16.

19 designates the rear wall of the box, which may be of metal or similar material, and is secured to the ring 17 by the screws 20 or similar fastening devices, there being a layer of cementing material or the like 20^x interposed between the wall 19 and the rear of said hardened disk 16. 21 designates a neck or extension which is adapted to engage the tone arm 4, and which may be secured to the rear wall 19 of the disk by means of the fastening devices 22, which pass through a flange 23. The diaphragm 7 is held in position between the inner and outer annuli 8, which are constructed and located substantially as already described with reference to Fig. 2, the inner annulus 8 being seated in an annular groove in the hardened rubber wall or disk 16, while the outer annulus 8 being contained within a groove or seat 9 of the overhanging flange 10, said parts 9 and 10 being constructed and located substantially as already described with respect to Fig. 2. The stylus bar 11 may be secured to the diaphragm 7 by any

suitable or convenient means, and I preferably mount the head 24 of the stylus bar as seen in Fig. 5, wherein 25 represents a pivot point or bearing which is staked in said head 24 and the pivot points are in engagement 70 with the hardened or jewel bearings 26, which are carried in the threaded stems 27, which are in threaded engagement with or mounted in the bearings 28, which are cast or otherwise secured to the metal ring 17 by 75- the arms 29.

In Fig. 4, 30 designates the hardened, resilient, disk, wall or body portion of the sound box, the same being provided with the flanged member 31, which terminates in 80 the downwardly inturned, annular flange 32, between which latter and the body portion are secured the annuli 8, of the same construction as already described, whereby the diaphragm 7 is at all times held in 85 proper position, a recess 33 being provided so that the diaphragm is capable of a slight longitudinal play, as is the case in the construction seen in Figs. 2 and 3.

34 designates the rear wall of the sound 90 box, which may be composed of metal, and is preferably in threaded engagement with the hardened rubber portion 30 by means of the neck or extension 35, whereby the parts 30 and 34 can be assembled by merely 95 screwing them together, there being cementing material employed between the contiguous walls of said members 30 and 34 of the character already described in Fig. 3, if desired. After the parts 30 and 34 are 100 assembled, they may be held in position by means of dowel pins, screws or the like 38, if desired.

36 designates arms projecting forwardly from the rear walls 34, which may be cast or 105 otherwise secured thereto, said arms terminating in suitable bearings 37, which are of substantially the same construction as the bearings 28 heretofore described with reference to Figs. 3 and 5, and the stylus 110 bar 11 seen in Fig. 4 may be equipped with the pivotal jewel mounting seen in Fig. 5, if desired.

It will be seen that in all the embodiments of my invention, I employ a somewhat 115 thickened, hardened resilient wall, as 2, 16 or 30, the function of which in each instance is to absorb all surface noises or metallic, scratchy sounds, the resultant vocal and instrumental sounds being recorded 120 or reproduced in a pleasing and effective manner with a maximum degree of fidelity to the original. The metallic portions 5, 17 and 19 may be nickelated or gold-plated if desired, thereby adding greatly to the 125 attractive appearance of the device.

It will further be seen that in all the embodiments of my invention, the metallic members, as the rings 5 and 17, in the case of Figs. 2 and 3, or the rear wall 34 in the 130

case of Fig. 4, have cast or secured directly thereto, the supporting arms, wherein the lower portion of the stylus bar is mounted, so that my device can be very cheaply and expeditiously manufactured, and the number of parts will be reduced to a minimum.

The manner of attaching the sound box seen in Fig. 4 to the tone arm 4 will be substantially the same as that already described with respect to Fig. 3.

In the construction seen in Fig. 2, the opening 39 through the sound box body is in alinement with the tube 4, said opening 39, in the two latter figures, being in alinement with the passage leading to the tube or tone arm already described.

It will be apparent that while I have described the material of which my sound box body is composed as being preferably of rubber cured to a degree simulating the human throat or palate, I do not desire to be limited thereto in every instance, as I may employ any other suitable plastic material capable of being cured or hardened to the required degree and having properties similar to rubber or its equivalent. I have therefore employed the term "rubber" or its equivalent, as a generic designation of any material which has the general characteristics of rubber when used as a reproducing agent, such as celluloid, bakelite, electrose, wood fiber, or the like, all of which I have found in practice to possess substantially the same acoustical properties as hard rubber, and it will be further understood that by the generic term "rubber" I comprehend rubber commingled or cured with the usual or any other desired ingredients which will produce a structure or substance simulating hard rubber or its equivalent.

In Fig. 6, I have shown another embodiment of my invention, wherein 40 designates the sound box, the rear disk, wall or body 41 thereof being composed of hardened, resilient material such as rubber or the like, and the same being provided with the rearwardly extending neck or extension 42, which may be softer than said body portion 41 so as to frictionally engage the tone arm 4. The extension 42 has the passage 43 therin, which is open at its rear portion, but closed at its forward portion, the sound waves being communicated to said passage 43 by means of the converging sound conveying ports or passages 44, which extend from the front face 45 of the disk or wall 41 and converge into the sound conveying passage 43. The diaphragm 7 is held between the annular beads or convex portions 46 and 47 of the diaphragm retaining member 48, the initial construction of the latter being apparent from Fig. 7, said diaphragm retaining member comprising the wall 49, which terminates in the convex or bead like portions 46 and 47, which have the passages

50 therethrough, said diaphragm retaining member being held in position against the front face 45 of the disk or hardened rubber wall 41 by means of the flange 51 of the ring 52, which may be in threaded or other engagement with the outer periphery of the disk or wall 41, any suitable adhesive or cementing material, such as shellac, or the like, being interposed between the threaded portions of the ring 52 and the disk or 75 wall 41.

In practice, I prefer to lay out the converging sound conveying ports or passages 44 so that the conjoint area of the same will be substantially the same as the area of the 80 passage 43 in the extension 42. The manner of constructing the diaphragm retaining member 48 will be apparent from Fig. 7, the same being made initially in the form of a strip, which can be cut off to the desired 85 lengths and bent into the position seen in Fig. 6. By means of this construction, an efficient and durable diaphragm retaining device is produced which will permit the diaphragm to have the requisite amount of 90 vibration at its outer as well as at its inner portions.

I have deemed it unnecessary to show the manner of attaching and supporting the stylus bar and its adjuncts in connection 95 with Fig. 6, as any of the constructions heretofore described may be employed or any other approved manner of mounting the stylus bar and its adjuncts.

It will be apparent to those skilled in the 100 art that by the employment of the converging sound conveying ports or passages 44, the action of the diaphragm 7 throughout its entire area is not retarded, but it is allowed to vibrate uniformly throughout its 105 entire area so that any crackling or improper bending or vibration of the same is prevented, and the sounds reproduced will be distributed and discharged from the entire area of the diaphragm in converging 110 lines toward the opening or passage 43 and thence to the desired point.

It will also be apparent that any choking between any portion of the diaphragm 7 and the front face 45 of the rear wall will 115 be prevented, which is a common occurrence in sound boxes of the prior art with which I am familiar.

It will now be apparent that I have devised a novel and useful construction of a 120 sound box for talking machines which embodies the features of advantage enumerated as desirable in the statement of the invention and the above description, and while I have in the present instance, shown and described 125 preferred embodiments thereof which will be found in practice to give satisfactory and reliable results, it is to be understood that the same is susceptible of modification in various particulars without departing from 130

the spirit or scope of the invention or sacrificing any of its advantages.

Having thus described my invention, what I claim as new and desire to secure by Letters Patent is:

1. In a sound-box, a rear wall comprising a thickened disk of non-metallic material, an extension of softer material on the rear wall of said disk adapted to engage a tone arm, a sound conveying passage in said extension open at its rear and closed at its front portion, and a plurality of sound conveying passages converging from the front face of said disk to said passage in said extension.
  2. In a sound box, a rear wall, comprising a disk of hardened rubber, an integral extension of softer rubber on said disk adapted to engage a tone arm, a sound conveying passage in said extension, open at its rear and closed at its front portion, and a plurality of sound conveying passages converging from the front face of said disk to said passage in said extension.
  3. In a sound box, a rear wall, comprising a disk of hardened rubber, an integral extension of softer rubber on said disk adapted to engage a tone arm, a sound conveying pas-
- sage in said extension, open at its rear and closed at its front portion, and a plurality of sound conveying passages converging from the front face of said disk to said passage in said extension.
4. In a sound box, a rear wall, comprising a disk of hardened rubber, an integral extension of softer rubber on said disk adapted to engage a tone arm, a sound conveying passage in said extension, open at its rear and closed at its front portion, and a plurality of sound conveying passages converging from the front face of said disk to said passage in said extension, the area of said plurality of sound conveying passages being substantially the same as the area of said passage in said extension, in combination with a diaphragm and means for securing said diaphragm in juxtaposition to said front face of said disk.

ALVA D. JONES.
